UNITED STATES PATENT OFFICE.

ROSA GOSDEN, OF MIDHURST, ENGLAND.

DESIGN FOR A BIDET.

SPECIFICATION forming part of Design No. 22,729, dated August 22, 1893.

Application filed November 14, 1892. Serial No. 452,009. Term of patent 7 years. Patented in England August 25, 1892, No. 15,291.

To all whom it may concern:

Be it known that I, ROSA GOSDEN, a subject of the Queen of Great Britain, residing at Midhurst, England, have invented and produced a new and original Design for Bidets or Hip-Baths, (for which I have obtained a patent in Great Britain, No. 15,291, dated August 25, 1892,) of which the following is a specification, reference being had to the accompanying drawings, showing a part thereof.

Figure 1 is a plan of my bidet or hip-bath stand with outer lid removed. Fig. 2 is a side elevation of the same.

The leading feature of my design consists

of a square frame or stand with semi-circular 15 grooves *d. d.*

What I claim, and desire to secure by Design Patent, is—

The design for a bidet or hip bath stand herein shown and described.

In testimony that I claim the foregoing I have hereunto set my hand this 30th day of September, 1892.

ROSA GOSDEN.
